(57) **CLAIM**

The ornamental design for a hair comb, as shown and described.

DESCRIPTION

FIG. 1 is a front view of the hair comb.

FIG. 2 is a rear view of the claimed design.

FIG. 3 is a left side view of the claimed design.

FIG. 4 is a right side view of the claimed design.

FIG. 5 is a top view of the claimed design.

FIG. 6 is a bottom view of the claimed design.

FIG. 7 is a perspective view of the claimed design; and, FIG. 8 is an enlarged view of the encircled portion "8" shown in FIG. 7.

The evenly spaced broken lines in FIGS. 7 and 8 are for the purpose of illustrating enlarged view indicators and form no part of the claimed design.

1 Claim, 4 Drawing Sheets
